METHOD OF AND APPARATUS FOR FORMING VENETIAN BLIND SLATS

Filed Feb. 9, 1942

UNITED STATES PATENT OFFICE

2,370,215

METHOD OF AND APPARATUS FOR FORMING VENETIAN BLIND SLATS

Allen B. Wilson, Evanston, Ill., assignor to Acme Steel Company, Chicago, Ill., a corporation of Illinois

Application February 9, 1942, Serial No. 430,012

12 Claims. (Cl. 153—2)

This invention relates to methods of and apparatus for forming metallic Venetian blind slats and the like, and its purpose is to provide improved means for carrying on in a continuous process the operations of stretching commercial strip steel or other metal and forming therefrom slats or other articles which are straight and of a curved or other non-planar cross section. The present invention is an improvement upon that described and claimed in the copending application of Joseph L. Hunter, Serial No. 279,391, filed June 19, 1939.

In order that a Venetian blind slat may have the required stiffness when it is formed of thin metal, it is necessary that it have a curved or other non-planar cross section, and strips having this characteristic and also having parallel edges may be used advantageously for other purposes. It has been found that commercial strip steel, as it comes from the mills, is not well adapted for the commercial manufacture of Venetian blind slats because it is not perfectly flat and has variations in temper and gauge distributed more or less throughout its entire length and area, so that attempts to convert a commercial strip into a form having a curved or other non-planar cross section by any of the usual rolling and bending processes have resulted in products which are not straight and do not have parallel edges.

In my copending application Serial No. 239,229, filed November 7, 1938, upon which Letters Patent of the United States No. 2,294,434 were issued on September 1, 1942, there is disclosed a method and apparatus for overcoming the above-mentioned difficulties by a two-stage process. In the first of these stages, the intermediate portion of the elongated metal strip is stretched longitudinally by a stress exceeding the elastic limit of the metal, the degree of tension exerted upon the metal being such that the irregularities in the portion subjected to the stretching operation are removed so that all parts of this intermediate portion would be under compression if the tension were released. Having thereby established a known condition in the metal strip, as distinguished from the uncertain and unknown condition existing in the commercial material at the beginning of the process, the strip is then subjected to the second stage of the process which consists in bending it transversely between rolls while supporting it in advance of and following the rolls in such a manner that tensile stresses are set up in the strip between the points of support and the marginal portions of the strip at the place of bending, thereby causing the lateral por-

tions of the strip to be stretched longitudinally to substantially the same extent that the intermediate portion was stretched in the first stage of the process. The elongated strip then emerges from the second stage of the process as a straight member having a bowed cross section and parallel longitudinal edges.

In the said application of Joseph L. Hunter, there is illustrated and described a form of apparatus for carrying out the two-stage process above referred to but the means for carrying out the first stage of the method differs from that specifically illustrated in my said copending application in that the intermediate portion of the strip is stretched by drawing it under tension through confining blocks forming a plurality of passages of curved cross section which have relative angularity longitudinally of the strip, whereas, as illustrated in my said copending application, the intermediate portion is stretched by passing it endwise over a crowned roller while under tension sufficient to effect the stretching of the desired portion.

The present invention is based upon the discovery that the above-described two-stage method may be practiced without the use of auxiliary supports in advance of and following the forming rolls which impart the transverse curvature to the strip and that this simplification may be accomplished by employing in the first stage the relatively inclined sets of blocks, disclosed in said application of Joseph L. Hunter, and so adjusting the relative inclination of the successive sets of blocks as to cause to be effected in the first stage that precise relative elongation of different laterally displaced parts of the strip which will have the effect of causing the strip to emerge from the forming rolls of the second stage as a member of bowed cross section and parallel edges which is either straight or of any other desired longitudinal shape. By this improved method the strip passes directly from the first stage to the second stage and the relative stretching of the intermediate portion and the lateral edge portions is so regulated in the first stage that the strip will coact with the forming rolls and assume a curved cross section and a straight form. By this improvement both the apparatus and the method are simplified and the apparatus of the first stage may be readily adjusted while the stretching and forming are in progress in order to cause the final product to have the desired form. Other objects of the invention relate to various features of construction and arrangement of the apparatus

and to details of the method which will appear more fully hereinafter.

The nature of the invention will be understood from the following specification taken with the accompanying drawing in which one example of the improved method and one form of the improved apparatus are illustrated. In the drawing,

Figure 1 shows a partial side elevation of the improved apparatus of the present invention;

Fig. 2 shows an enlarged longitudinal vertical section through the die blocks illustrated in Fig. 1 through which the metal strip is drawn to effect the stretching of the intermediate portion thereof;

Fig. 3 shows a transverse section taken on the line 3—3 of Fig. 1;

Fig. 4 shows an enlarged vertical section on the line 4—4 of Fig. 1; and

Fig. 5 shows a perspective view of a portion of one of the completed slats.

As illustrated in the drawing, the strip metal employed in the practice of the present invention, which metal may preferably be thin steel which is hard and resilient, is wound in a coil supplied from a reel 8 from which it passes around an idler roller 9 and then around a friction drag roller 10 having an outer surface of rubber or the like and provided with an adjusting device 10^a which may be regulated for varying the resistance to the rotation of the roller for retarding the movement of the metal strip 11 as it is unwound from the coil. This metal strip is withdrawn from the reel 8 under tension and is moved through confining passages in two sets of die blocks 12 and 13 and, after emerging from the second set of die blocks, the strip passes between forming rolls 14 and 15 provided with complementary concave and convex peripheral surfaces, respectively, which may conform to the arc of a circle, and which bend the strip transversely as it passes therethrough in a continuous operation. The forming rolls 14 and 15 may be relied upon to feed the strip through the apparatus and maintain tension therein, in which case the roll 15 will have a peripheral surface of rubber or the like, or the strip may be drawn through the rolls 14 and 15, as well as through the die blocks 12 and 13, by power driven drive rollers 29 and 30 which maintain sufficient tension in the strip to bring about the stretching of the metal in the manner hereinafter referred to.

The set of die blocks 12 comprises an upper block 12^a and a lower block 12^b which are provided with complementary concave and convex surfaces, respectively, extending transversely thereof to form between them a confining passage of arcuate cross section concaved downwardly and of substantially the same width as the strip, the height of the passage being only slightly greater than the thickness of the metal strip to be treated so that the upper and lower sides of the strip are engaged by the blocks 12^a and 12^b, respectively, during the passage of the strip therethrough. The blocks 12^a and 12^b are secured together and maintained in the desired spaced relation by side plates 12^c which are secured to the blocks by screws 12^d. The side plates 12^c are provided with rearwardly extending arms 12^e having rotatably mounted between them a guide roller 16 which is adapted to contact with the underside of the strip 11 as it is withdrawn from the reel so that the strip is caused to follow a fixed path as it enters one of the die blocks 12, regardless of the angular position of this block.

The other set of die blocks 13 comprises an up-

per block 13^a and a lower block 13^b which are secured together and spaced apart by side plates 13^c secured in position by screws 13^d. These die blocks 13^a and 13^b are also provided with opposed concave and convex surfaces, respectively, which form between them a restricted passage of arcuate cross section concaved downwardly and formed by radii having a common center, these surfaces preferably having the same width and curvature and the same spaced relation as the corresponding surfaces formed on the die blocks 12. The side plates 13^c are provided with rearwardly extending ears 13^e which project between similar ears 12^f formed on the side plates 12^c. These ears are pivotally connected by pins 11 and are adapted to permit the die blocks 12 to be swung angularly with respect to the die blocks 13 so that the angularity of the restricted passages through the two sets of die blocks may be regulated.

The die blocks 13 are adapted to be secured upon a fixed support, not illustrated, and the side plates 13^c are extended above the upper die block 13^a where they are secured to a bar 18 extending between them and engaged by the screws 19 which pass through apertures in the side plates. The bar 18 projects from the die blocks 13 and is offset upwardly and rearwardly to provide a support for the rear portion of the die blocks 12. For this purpose, the side plates 12^c are provided with another pair of upwardly extending ears 12^g having a pivotal engagement by means of the pin 28 with an eye-bolt 21. This bolt extends upwardly through an elongated slot 18^a formed in the bar 18 and is engaged beneath the bar by a washer 22 and a wing nut 23. On the upper side of the bar, the bolt is engaged by a washer 24 and a wing nut 25. It will be apparent that by adjusting the wing nuts 23 and 25 the rear end of the set of die blocks 12 may be raised or lowered in order to change the angularity of the passage between the blocks 12^a and 12^b with respect to the passage between the blocks 13^a and 13^b. The cylindrical roller 16 which engages the underside of the commercial strip material being withdrawn from the reel 8 is adapted to maintain the strip in alignment with the passage between the blocks 12^a and 12^b as it enters that passage, regardless of the angular positions of these blocks.

Due to the curvature of the passages between the die blocks, it will be apparent that the intermediate portion of the part 11^a of the strip which is passing through the gap between the two die blocks must travel a longer path than the edge portions which are nearer to the pivot 17 which connects the two sets of blocks. Inasmuch as all parts of the strip must travel at the same speed, this difference in the distance through which different parts of the strip must pass, in going from one set of blocks to the other, results in a permanent stretching or elongation of the intermediate portion of the strip. The width of the portion of the strip which is thus stretched and the relative extents of the stretching of different portions of the strip which are laterally displaced from each other may be regulated by adjusting the wing nuts 23 and 25 and thereby effecting a corresponding adjustment of the longitudinal inclination of the passage between the die blocks 12 with respect to the corresponding passage through the die blocks 13. For example, by increasing this angle, as a result of lowering the rear end of the die blocks 12, the stretching or permanent elongation of the intermediate portion of the strip may be increased

with respect to the edge portions. By suitably adjusting the blocks the permanent stretching which is effected in the blocks 12 and 13 may be caused to extend throughout a major portion of the width of the strip although varying in magnitude in different laterally displaced parts of the strip. In some cases the commercial strip material may have its center portion elongated as it comes from the supply reel and, in that event, it may be desirable to effect some permanent stretching of the edge portions of the strip as it passes through the sets of blocks 12 and 13. This may be done by raising the blocks 12, as indicated by dotted lines in Fig. 2, thus causing the edge portions of the strip to pass through a longer gap than the center portion in traveling from one set of blocks to the other.

After emerging from the die blocks 12, the strip 11 is carried through the forming rollers 14 and 15 which are secured on shafts 27 and 28, respectively, these shafts being power driven in the directions indicated by the arrows. The laterally curved peripheral surfaces 14^a and 15^a of the rollers 14 and 15, respectively, are spaced apart, as shown in Fig. 4, a distance substantially equal to the thickness or gauge of the metal strip being operated upon and these peripheral surfaces, at the point where they are in closest proximity to each other, are in horizontal alignment with the passage between the blocks 13^a and 13^b, with respect to which these forming rollers are preferably located in close proximity. As the strip 11 passes between the rollers 14 and 15, it is bent transversely to conform to the curvatures of the surfaces 14^a and 15^a and, since the resilient metal has a tendency to spring back partially toward its original condition after being bent therefrom, the surfaces 14^a and 15^a preferably have a curvature which is substantially greater than that described in the finished slat. After being thus bent transversely, the metal strip emerges from the rolls 14 and 15 as a straight member 11^b which has parallel edges and a uniform transverse curvature somewhat less than that of the peripheral surfaces of the forming rolls. This metal strip may then be cut off to form slats 31, having the form shown in Fig. 5. If these slats have been formed of thin resilient hard material, such as that which is preferably employed for the manufacture of metallic Venetian blind slats, it will be found that these slats will return automatically to the straight form shown in Fig. 5 when bent therefrom and that they will maintain the desired parallel relationship when a number of them are grouped together in the usual manner in a Venetian blind. Although the rolls 14 and 15 may supply the power for moving the strip and maintaining the necessary degree of tension therein, the strip may be drawn under tension through the rolls 14 and 15, as well as through the blocks 12 and 13, by power actuated driving rolls 29 and 30 which engage opposite sides of the strip and which have cylindrical peripheral surfaces. The rolls 29 and 30 are preferably formed of steel and the metal strip, after passing around substantially one-half of the peripheral surface of the roll 29, is reversed and passed around the major portion of the roll 30 with which it is maintained in close contact by the pressure roll 33 having a peripheral portion formed of rubber or the like. The rolls 29 and 30 are of the same diameters and are power driven, being geared together so that their peripheral portions travel at the same speed. In passing around the rolls 29

and 30 the concave strip is temporarily flattened but promptly resumes its normal transverse curvature due to the resilience of the metal.

If, during the operation of the apparatus, it is found that the portion 11^b is not straight, or does not have any other longitudinal shape which is desired, this may be corrected by adjusting the wing nuts 23 and 25 to effect a corresponding adjustment of the angularity of the die blocks 12 with respect to the die blocks 13, since it has been discovered that by suitably regulating the relative longitudinal stretching of different laterally displaced portions of the strip, as it passes through the die blocks 12 and 13, the strip may be caused to assume any desired longitudinal shape, within reasonable limits, when it emerges from the forming rolls 14 and 15. The concavity of the passages through the die blocks 12 and 13 and the concavity of the passage between the forming rollers 14 and 15 are both directed downwardly and the relative longitudinal angularity of the passages through the die blocks 12 and 13 is also directed downwardly. The passages through the die blocks are preferably straight longitudinally although they might have other shapes with a similar effect. The major portion of the longitudinal stretching, by which the inequalities in the internal stresses in the metal are removed in the final product, may be effected largely or wholly by the die blocks but, in general, there will be some longitudinal stretching of the lateral edge portions of the strip as it passes through the forming rolls by reason of the fact that, due to the increased concavity of the strip 35 at the place where it contacts the forming rolls, as compared with its shape at places in advance of and following said rolls, the edge portions of the strip are compelled to travel longer paths than the intermediate portions of the strip as they pass through the region which includes the forming rolls. In any case, the entire operation is carried on as a continuous process and when the parts are adjusted to produce a final product which is longitudinally straight, it is believed that all parts of the strip will have been stretched longitudinally to substantially the same degree.

Although one form of the improved apparatus and one example of the improved method have been illustrated and described, it will be understood that the apparatus may take various forms and that the method may be practiced in various ways without departing from the scope of the appended claims.

I claim:

1. The method of forming a metal strip having a predetermined longitudinal shape and a non-planer cross section, which consists in passing the strip through a plurality of confining passages of curved cross section which are relatively inclined longitudinally of the strip, then bending the strip transversely to approximate the desired non-planer cross section, maintaining longitudinal tension in the strip while it is passing through said passages and while it is being bent transversely, and adjusting the relative inclination of said passages and thereby regulating the longitudinal shape of the final product which follows said transverse bending.

2. The method of forming in a continuous process a straight metal strip having a curved cross section, which consists in passing the strip under longitudinal tension through successive confining passages of curved lateral cross section which are relatively inclined longitudinally with respect to each other, then immediately

confining the moving strip and bending it transversely while moving it endwise and maintaining said longitudinal tension therein, and adjusting the relative inclination of said passages and thereby causing the strip to emerge from the transverse bending operation as a straight strip having a curved cross section.

3. The combination in apparatus for forming a metal strip having a predetermined longitudinal shape and a non-planar cross section, of a plurality of sets of die blocks each having a longitudinal strip confining passage therethrough which is transversely curved, said passages in said die blocks being relatively inclined longitudinally, forming rolls having non-planar peripheral surfaces adapted to receive a metal strip between them, means for pulling a metal strip endwise through the passages of said die blocks and then between said forming rolls, and means for adjusting the relative inclination of said sets of die blocks and thereby causing the metal strip to emerge from said forming rolls with the desired longitudinal shape.

4. The combination in apparatus for forming a metal strip having a predetermined longitudinal shape and a non-planar cross section, of a plurality of sets of die blocks each having a longitudinal strip confining passage therethrough which is transversely curved, said passages in said die blocks being relatively inclined longitudinally, forming rolls having non-planar peripheral surfaces adapted to bend the strip transversely and to pull it through said blocks, and means for adjusting the relative inclination of said blocks and thereby regulating the longitudinal stretching of the metal between successive die blocks and causing the metal strip to emerge from said forming rolls with the desired longitudinal shape.

5. The combination in apparatus for forming a metal strip having a predetermined longitudinal shape and a non-planar cross section, of a plurality of sets of die blocks each having a longitudinal passage therethrough which is transversely curved, said passages in said die blocks being relatively inclined longitudinally and having a width and height substantially equal to the width and thickness of said strip, forming rolls having non-planar peripheral surfaces adapted to bend the strip transversely and to pull it through said blocks, means for adjusting the relative inclination of said blocks and thereby causing the metal to emerge from said forming rolls with the desired longitudinal shape, and means for causing the metal strip to enter the passage of the first die blocks at the same angle with respect to said first die blocks in all relative positions of the sets of die blocks.

6. The combination in apparatus for forming a metal strip having a predetermined longitudinal shape and a non-planar cross section, of a plurality of sets of die blocks each having a longitudinal passage therethrough which is transversely curved, said passages in said die blocks being relatively inclined longitudinally and having a width and height substantially equal to the width and thickness of said strip, forming rolls having non-planar peripheral surfaces adapted to receive a metal strip between them, means for pulling a metal strip endwise through the passage of said die blocks and then between said forming rolls, means for adjusting the relative inclination of said sets of die blocks and thereby causing the metal strip to emerge from said forming rolls with the desired longitudinal shape, and means for causing the metal strip to

enter the passage of the first die blocks at the same angle with respect to said first die blocks in all relative angular positions of the sets of die blocks.

7. The combination in apparatus for forming a metal strip having a predetermined longitudinal shape and a non-planar cross section, of a plurality of sets of die blocks each having a longitudinal passage therethrough which is transversely curved, said passages in said die blocks being relatively inclined longitudinally, forming rolls having non-planar peripheral surfaces adapted to receive a metal strip between them, means for pulling a metal strip endwise through the passages of said die blocks and then between said forming rolls, means for adjusting the relative inclination of said sets of die blocks and thereby causing the metal strip to emerge from said forming rolls with the desired longitudinal shape, and a roller carried by the first set of die blocks and movable therewith for supporting the metal strip in advance of said die blocks.

8. The combination in apparatus for forming a metal strip having a predetermined longitudinal shape and a non-planar cross section, of a plurality of sets of die blocks having longitudinal confining passages therethrough which are of non-planar cross section and which are relatively inclined in adjacent sets of die blocks, means for moving endwise through said passages a long metal strip which is initially substantially flat, means for supporting one set of die blocks from the adjacent set, means for adjusting the angular position of the set of die blocks which is so supported, and means carried by said last-mentioned set of die blocks for supporting the metal strip in advance of that set of die blocks.

9. The combination in apparatus for forming a metal strip having a predetermined longitudinal shape and a non-planar cross section, of a plurality of sets of die blocks having longitudinal confining passages therethrough which are of non-planar cross section and which are relatively inclined in adjacent sets of die blocks, means for moving endwise through said passages a long metal strip which is initially substantially flat, means for supporting one set of die blocks from the adjacent set, means for adjusting said one set of die blocks angularly with respect to said adjacent set through a sufficient range to reverse the relative inclination of said passages, and means movable with said one set of die blocks for causing said metal strip to enter the passage of said one set of die blocks at the same angle in all relative positions of said one set of die blocks.

10. The method of forming in a continuous process a straight metal strip having a curved cross section, which consists in passing the strip under longitudinal tension through successive confining passages of curved cross section which are located in proximity to each other and which are relatively inclined longitudinally, preventing transverse displacement of the strip during its travel through said passages, then immediately confining the moving strip and bending it transversely while moving it endwise and maintaining said longitudinal tension therein, and adjusting the relative inclination of said passages and thereby regulating the longitudinal stretching of different laterally displaced portions of the strip as it passes from one of said passages to the other and causing the strip to emerge from the transverse bending operation as a straight strip having a curved cross section.

11. The method of forming in a continuous process a metal strip having a predetermined longitudinal shape and a non-planar cross section, which consists in moving a substantially flat strip endwise and continuously curving advancing portions of the strip transversely and thereby stressing it within its elastic limit while bending the transversely curved portion of the strip longitudinally during its movement and thereby causing one part of the strip to be elongated with respect to other laterally displaced parts thereof, then bending the strip transversely and thereby stressing it beyond its elastic limit and confining it to a non-planar cross section, and adjusting the degree of said longitudinal bending of the strip and thereby regulating the longitudinal shape of the final product.

12. The method of forming in a continuous process a straight metal strip having a curved cross section, comprising a first stage which consists in curving a substantially flat metal strip transversely, and moving it endwise along a transversely curved and longitudinally bent path and thereby effecting the elongation of the intermediate portions of the strip with respect to the lateral edge portions thereof, a second stage which consists in bending the strip transversely and moving it endwise, and the step of regulating the relative elongation of the intermediate portions and the lateral edge portions of the strip in said first stage and thereby determining the longitudinal shape of the strip emerging from said second stage.

ALLEN B. WILSON.
